SOLE PRESSING MACHINE

Lawrence E. Steimen, Beverly, Mass., assignor to
United Shoe Machinery Corporation, Flemington, N. J., a corporation of New Jersey

Application July 30, 1942, Serial No. 452,859

9 Claims. (Cl. 12—38)

This invention relates to sole-laying or sole-pressing machines and is herein illustrated as embodied in a machine particularly adapted to laying a straight-edge sole upon the bottom of a lasted shoe to which the sole is to be vulcanized. The term "straight-edge sole" denotes a sole which has a straight edge in the finished shoe as distinguished from one having, for example, a rolled or semi-rolled edge, such as is commonly present in gaiters, that is, a sole all portions of which are as flat as the bottom of the shoe. A common example of a straight-edge sole is one having an extension edge around the forepart.

After the lasted shoe is otherwise substantially completed, except for the sole-laying and vulcanizing steps, a sole of unvulcanized or partly vulcanized rubber is properly located on the bottom of the shoe and is laid or pressed into place. Commonly this sole-laying operation is performed by a machine comprising a pressure box having a flexible diaphragm upon which the shoe, with the sole lightly adhering to its bottom, is placed, the shoe being supported against pressure which is exerted through the diaphragm by means of a suitable support which comprises a jack for engaging the top of the last and a toe rest for engaging the top of the forepart of the shoe. A machine of this general type, and specifically a machine in which fluid is forced into the pressure box beneath the diaphragm, is disclosed in United States Letters Patent No. 1,920,977, granted August 8, 1933 on an application filed in the name of Sidney J. Finn.

In order to facilitate the pressing or laying of straight-edge soles, there is provided in a machine in which fluid pressure is applied through a flexible diaphragm, a device adapted to be placed upon the diaphragm, said device comprising a comparatively thick pad of flexible resilient material, such for example as rubber, and a rigid holder consisting of an endless wall having inwardly extending flanges to receive marginal portions of the pad with a sliding fit. This device is supported against the pressure exerted through the diaphragm only by the shoe which is itself properly supported, no part of the device engaging any part of the machine other than the diaphragm upon which the device rests. The device may therefore be said to be a floating one in that its position during the application of pressure may vary according to the type of shoe being operated upon, the thickness of the pad and the flanges of the rigid holder preventing any considerable bending of the pad about the forepart and the heelpart of the sole. Preferably the pad has a portion of

increased flexibility and compressibility at a locality where it acts to press the sole into the arch of a shoe, if the shoe has an arch; and in case the arch is a high one, the pad may be provided with a tongue which is crowded up into the arch by the pressure exerted through the diaphragm.

These and other features of the invention, including certain details of construction and combinations of parts, will be described as embodied in an illustrated machine and pointed out in the appended claims.

Referring now to the accompanying drawings, Fig. 1 is a vertical section through a portion of a machine in which the present invention is embodied, a high-arched shoe with a straight-edge sole and having a wood heel being shown in the position which it occupies before pressure is applied;

Fig. 2 is a section similar to Fig. 1 but showing the shoe while pressure is being applied;

Fig. 3 is a perspective of the pad and its holder; and

Fig. 4 is a perspective of a modified pad in the same holder.

The illustrated machine comprises a pressure box 5, the upper wall of which consists of a flexible diaphragm 7, herein shown as comprising three layers of sheet rubber. Disregarding for the moment the pad and its holder which will be described later, the operation of the machine is substantially as follows. A lasted shoe 100 with a sole 200 located thereon is placed on the diaphragm 7 with its heel end against a heel plate 9 having a piece of yielding material 11, such as rubber, on its edge. Thereafter, a jack post, not shown, is swung into position over the top of the last 300, two side plates, one being shown at 12, and a toe plate 15 are slid horizontally so that their inner edges contact with the shoe; and a toe rest 17, carried by the toe plate, is brought down upon the toe portion of the shoe in the manner shown in Fig. 2. A fluid, such as water, is now forced into the pressure box by a piston 19 to distend the diaphragm and press the sole. After the sole has thus been pressed or laid, the parts return to the position shown in Fig. 1 to permit removal of the shoe. No further description of the construction and the mode of operation of the machine, as thus far described, will be given, since any suitable machine may be employed in which a flexible diaphragm is used, reference being made to the patent for details of construction of the particular machine shown.

The device which is placed upon the diaphragm consists of a holder of rigid material, such as

steel, having substantially straight parallel side walls 31, 33 connected by curved end walls 35, 37. Around the forepart are two horizontal flanges, an upper flange 39 and a lower flange 41, which hold the forepart of a comparatively thick pad 43 of flexible resilient material in place and prevent the pad from bulging up around the forepart of the sole. Around the rear part are two upper flanges 45 and two lower flanges 47, the function of these two pairs of flanges being to maintain the heel end of the pad in the holder and to prevent the pad from bulging up around the heel parts of soles of certain types of shoes. The proportions are such that the pad has a sliding fit in the holder. It may thus be readily removed and replaced by another pad of the same or different construction, and the ends may slide toward each other when force is applied to a locality near the longitudinal middle of the pad to cause that locality to bulge up into the recess just in front of the heel of a shoe, this latter capability being particularly advantageous in the modified construction of Fig. 4 which has no tongue.

The pad shown in Figs. 1, 2 and 3 is particularly adapted for use with shoes having high arches. To this end there is formed in this pad a tongue 49 which is generally trapezoidal in longitudinal section and is integral with the pad at the forward end of the tongue. The shoe shown in Figs. 1 and 2 is one which presents considerable difficulty. The sole, which has an extension edge around the forepart, has been properly located on the bottom of the shoe and lightly cemented in place, and the heel has been similarly located and is similarly held. In Fig. 1, before pressure has been applied, the tongue 49 has been swung up somewhat, owing to the fact that its lower corner rests upon the undistended diaphragm 7. When now fluid is forced into the pressure box to distend the diaphragm, the tongue is swung up and crowded into the recess at the shank of the shoe, as shown in Fig. 2. In order to permit the tongue to swing up freely, particularly when shoes having very high arches are being operated upon, the lower edge of that portion of the heel end of the pad which faces the tongue is cut away somewhat as indicated in Figs. 1 and 2. In order that the tongue may readily be caused to accommodate its shape to the longitudinal shape of the recess into which it is forced as well as to wrap somewhat about the edges at the shank portion of the sole, the tongue is made more flexible and compressible than it would otherwise be, for example by cutting in its under side a series of transverse slots 51, the slots being preferably of graduated depth, as shown. After the pressing operation, the shoe is put in a vulcanizing oven; and after vulcanization the last is pulled and the heel nailed.

The shoe illustrated in Figs. 1 and 2 has been chosen for illustration because of the difficulties encountered in the pressing operation. It should be particularly noted that the thick pad and the overhanging flanges at the forepart provide a construction in which a straight-edge sole, for example one with an extension edge such as is shown, is neither bent nor rolled but is maintained substantially as flat as is the bottom of the lasted shoe against which it is pressed.

In the case of shoes which have low arches or none at all and in which the sole commonly extends over the heel end of the lasted shoe, a pad such as that shown in Fig. 4 may be used. In

this case the holder is the same, but the pad 53 is a thick piece of flexible resilient material of substantially uniform thickness throughout. In such a pad it is desirable that a portion spaced from the ends, which is bulged up when a shoe having an arch is being operated upon, should be of increased flexibility and compressibility. To this end it may contain less material than the two ends of the pad by reason of a series of slots 55 cut in its under side. It will be noted that, in the illustrated embodiment, the slots are of graduated depth, being deeper near the middle portion of the series than at the ends. There is thus somewhat more material at the two ends of the bulged portion, and particularly at the rear end where the bend is usually sharper.

In the operation of the machine, the pad holder with its pad is placed upon the diaphragm in proper position; and the shoe with the sole properly located thereon is placed upon the pad. This is the position of parts shown in Fig. 1. The treadle of the machine is then depressed, whereupon the jack swings into a position just above the top of the last, the side and toe plates close about the shoe, and the toe rest 17 descends upon the toe portion of the shoe. A fluid is then forced into the pressure box 5 to distend the diaphragm and produce the effect shown in Fig. 2. The pressing operation is now complete, and the parts of the machine returned to the position shown in Fig. 1 to permit removal of the shoe.

The device is shown as occupying a position which is substantially horizontal but it should be understood that it may occupy a tilted position depending upon the position taken by the shoe when the pressure is applied. It should be particularly noted that the whole device is supported against the pressure exerted through the diaphragm entirely by the bottom of the forepart and heel of the shoe, if the shoe has an arch, or by the flat bottom of the sole if the shoe has no arch. Inasmuch as the device accommodates itself to the position of the bottom of the shoe independently of the positions occupied by other parts of the machine, the device is equally useful in machines of other types, such for example as those in which the shoe is pushed down upon the diaphragm, of a pressure box which holds a constant volume of liquid.

Although the invention has been set forth as embodied in a construction in which pressure is applied through a diaphragm by forcing a fluid into a pressure box, it should be understood that the invention is not limited in the scope of its application to the particular construction which has been shown and described.

Having thus described the invention, what I claim as new and desire to secure by Letters Patent of the United States is:

60. 1. A machine for pressing against the bottom of a lasted shoe a straight-edge sole, said machine having in combination a pressure box one wall of which comprises a flexible diaphragm, means for supporting the shoe against pressure applied through the diaphragm, a thick pad of resilient material located upon the diaphragm and with which the bottom of the sole of the shoe contacts, a pad holder of rigid material provided with flanges at its toe and heel ends to receive the pad and to prevent any considerable bending of the pad about the edges of the sole at those localities, and means for causing the diaphragm to exert pressure through the pad to press the sole against the bottom of the shoe, the holder being free to accommodate its position.

to any position occupied by the shoe during the application of the pressure.

2. A device for use with a sole-pressing machine having a flexible diaphragm, said device being adapted to be placed upon the diaphragm and comprising a comparatively thick pad of flexible material, and a rigid holder consisting of an endless wall having inwardly extending flanges at its toe and heel ends to receive marginal portions of the pad.

3. A device for use with a sole-pressing machine having a flexible diaphragm, said device being adapted to be placed upon the diaphragm and comprising a comparatively thick pad of flexible material, and a rigid holder consisting of an endless wall having inwardly extending flanges at its toe and heel ends to receive marginal portions of the pad, said pad having a portion spaced from the ends thereof which is of greater compressibility than are the end portions.

4. A device for use with a sole-pressing machine having a flexible diaphragm, said device being adapted to be placed upon the diaphragm and comprising a comparatively thick pad of flexible material, and a rigid holder consisting of an endless wall having inwardly extending flanges at its toe and heel ends to receive marginal portions of the pad, said pad having on the side next to the diaphragm and in a locality spaced from the ends of the pad a series of cut-away portions.

5. A device for use with a sole-pressing machine having a flexible diaphragm, said device being adapted to be placed upon the diaphragm and comprising a comparatively thick pad of flexible material provided at a locality between the ends thereof with a tongue, and a holder consisting of an endless wall having inwardly extending flanges to receive marginal portions of the pad.

6. A device for use with a sole-pressing machine having a flexible diaphragm, said device

being adapted to be placed upon the diaphragm and comprising a comparatively thick pad of flexible material provided at a locality between the ends thereof with a tongue, and a holder consisting of an endless wall having inwardly extending flanges to receive marginal portions of the pad, said tongue being more compressible than the remainder of the pad.

7. A device for use with a sole-pressing machine having a flexible diaphragm, said device being adapted to be placed upon the diaphragm and comprising a comparatively thick pad of flexible material provided at a locality between the ends thereof with a tongue, and a holder consisting of an endless wall having inwardly extending flanges to receive marginal portions of the pad, said tongue having a cut-away portion on the side next to the diaphragm.

8. A device for use with a sole-pressing machine having a flexible diaphragm, said device being adapted to be placed upon the diaphragm and comprising a comparatively thick pad of flexible material provided at a locality between the ends thereof with a tongue, and a holder consisting of an endless wall having inwardly extending flanges to receive marginal portions of the pad, said tongue being generally trapezoidal in longitudinal section with its larger end presented toward the rear of the pad.

9. A device for use with a sole-pressing machine having a flexible diaphragm, said device being adapted to be placed upon the diaphragm and comprising a comparatively thick pad of flexible material provided at a locality between the ends thereof with a tongue, and a holder consisting of an endless wall having inwardly extending flanges to receive marginal portions of the pad, said tongue being generally trapezoidal in longitudinal section and having on the side next to the diaphragm a series of cut-away portions.

LAWRENCE E. STEIMEN.
